US0D1013694S

(12) **United States Design Patent** (10) **Patent No.:** **US D1,013,694 S**
(45) **Date of Patent:** **** Feb. 6, 2024**

(54) **COVER FOR ELECTRONIC DEVICE**

(71) Applicant: **Shenzhen G-world Technology Incorporated Company**, Shenzhen (CN)

(72) Inventors: **Yi Lu**, Guangdong (CN); **Chuan Song**, Guangdong (CN)

(**) Term: **15 Years**

(21) Appl. No.: **35/515,958**

(22) Filed: **Dec. 15, 2022**

(80) **Hague Agreement Data**

Int. Filing Date: **Dec. 15, 2022**

Int. Reg. No.: **DM/225819**

Int. Reg. Date: **Dec. 15, 2022**

Int. Reg. Pub. Date: **Jan. 13, 2023**

(51) **LOC (14) Cl.** **14-02**

(52) **U.S. Cl.**

USPC **D14/440**

Assistant Examiner — Samina Vieth

(57) **CLAIM**

The ornamental design for a cover for electronic device, as shown and described.

DESCRIPTION

1 . Cover for electronic device

1.1 : Front

1.2 : Back

1.3 : Left

1.4 : Right

1.5 : Top

1.6 : Bottom

1.7 : Perspective

1.8 : Perspective

1.9 : Unfolded

1.10 : Unfolded

1.11 : Perspective view in a state of use

1.12 : Perspective view in a state of use

1.13 : Perspective view in a state of use

1.14 : Perspective view in a state of use

The figures include surface shading, which represents contours and not surface ornamentation.

(Continued)

The broken lines are included for the purpose of illustrating environmental structure and portions of the cover for electronic device, and form no part of the claimed design.

1 Claim, 14 Drawing Sheets
